UNITED STATES PATENT OFFICE.

GEORGE A. WEST, OF BUFFALO, NEW YORK, ASSIGNOR OF ONE-HALF TO
AUSTIN M. WEST, OF BUFFALO, NEW YORK.

SPARKER FOR EXPLOSIVE-ENGINES.

SPECIFICATION forming part of Letters Patent No. 788,868, dated May 2, 1905.

Application filed November 13, 1903. Serial No. 181,063.

To all whom it may concern:

Be it known that I, GEORGE A. WEST, a citizen of the United States, residing at Buffalo, in the county of Erie and State of New York, have invented a new and useful Sparker for Explosive-Engines, of which the following is a specification.

This invention relates to certain improvements in explosive-engines, and has for its principal object to provide a novel form of sparker in which a movable electrode is actuated by the pressure of the explosive charge.

A further object of the invention is to provide a sparker in which one of the electrodes is carried by a piston that is subjected to the pressure of the gases in the cylinder or explosion-chamber of the engine and is moved past a relatively stationary electrode during the compression-stroke of the main piston.

With these and other objects in view, as will hereinafter appear more fully, the invention consists in the novel construction and arrangement of parts hereinafter described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a sectional elevation of a sparker constructed in accordance with the invention. Fig. 2 is a similar view showing the positions when the two electrodes are in contact.

Similar numerals of reference are employed to indicate corresponding parts throughout both figures of the drawings.

The sparker forming the subject of the present invention is designed for use in connection with explosive-engines of any type, and the movable electrode is carried by a piston that is disposed within a suitable sleeve in communication with the explosion-chamber of the engine, so that the piston will be moved by the pressure of the explosive charge.

The explosion-chamber is tapped for the reception of the threaded end of a casing 70, at one side of which is a threaded opening for

the reception of a hollow plug 71, within which is a second plug or sleeve 72, separated from the first by an insulating-ring 73, the insulating material extending to the outside of the main plug and being confined in place by a ring or washer 75, that is pressed against the insulating material by a nut 76 on the threaded end of the sleeve. The sleeve forms a guide for a bar-electrode 77, having limited longitudinal movement. The outer end of the electrode is guided in a suitable opening formed in a yoke 78, against which bears one end of a spring 79, the opposite end of the spring bearing against a collar 80, carried by the electrode, and said collar serving by engagement with the end of the sleeve 72 to limit inward movement of the electrode. Outward movement of the electrode is limited by means of a pin 81, carried by said electrode and adapted to engage against the inner flanged end of the sleeve.

The upper portion of the casing 70 has a cylindrical bore for the reception of a small piston 85, to which is secured a bar-electrode 86, adapted to make wiping contact with the electrode 77. The upper end of the electrode 86 extends through a suitable opening in a cap-plate 88, covering the top of the casing and held in place by a ring-nut 89, while between the cap-plate and the upper end of the piston is a cushioning-spring 90, that serves to prevent injurious contact between the piston and the cap. The upper portion of the electrode 86 is threaded for the reception of a nut 92, which may be adjusted to alter the stroke of the piston 85. The electrode-bar 85 passes through an opening in a yoke 95, the lower ends of which are turned outward and seated in suitable recesses in the ring-nut, and between the lower face of the cross-bar of the yoke and an adjustable collar 96 on the bar-electrode is a helical compression-spring 97, that serves in part to cushion the upstroke of the piston.

In the operation of the sparker the suction-stroke of the main piston will create a partial vacuum below the small piston 85, and the latter will descend, the electrode 86 wiping past the electrode 7. The downward move-

ment of the piston is aided by the spring 97, and the spring has sufficient force to prevent the piston 85 moving upward at the starting of the compression-stroke. The descending movement of the piston may be accomplished by the spring 97 during the exhaust-stroke of the main piston; but in any case provision is made for breaking the sparking-circuit during downward movement of the piston, so that there will be no spark during the exhaust or suction strokes. Near the completion of the compression-stroke the piston 85 ascends against the stress of the spring 97 and wipes past the electrode 77, pushing the latter outward, and then on leaving the electrode 77 a spark is created and an explosive charge is ignited. The limit of downward movement of the electrode 86 is adjusted by nut 92, that comes into contact with the upper end of the yoke 95 at the completion of the stroke of the piston, and by adjusting this nut and by turning the nut 96 to alter the stress of the spring 97 the explosion may be timed in any desired manner and occur either at the completion of the compression-stroke or before or after the completion of such stroke, as circumstances may require. The adjustment of the resisting force of the spring 97 will permit it to yield under any desired degree of compression of the explosive charge, so that the explosion may occur at any desired point in the stroke of the piston of the engine, in which may be secured a plug 99, the opening being directly opposite the electrodes, so that on the removal of the plug the electrodes may be examined and cleaned, if necessary.

A sparker of the character described may be employed in connection with explosive-engines of any type and may be connected in any suitable sparking circuit; but it is preferred that provision be made for holding the circuit open during downward movement of the electrode 86, so that no spark may occur on this movement of the electrode.

Having thus described the invention, what is claimed is—

1. In a sparker for explosive-engines, a cylinder having one end in communication with the explosion-chamber of the engine, a piston disposed in said cylinder, an electrode carried by the piston, and a second electrode movable transversely of the first and adapted to be engaged and moved thereby as the piston is reciprocated, said electrodes having rounded or cam-shaped contact-faces to permit the wiping of one past the other.

2. In a sparker for explosive-engines, a cylinder having its inner end in communication with the explosion-chamber of the engine, a piston disposed in the cylinder, an electrode carried by the piston, a spring arranged between the outer face of the piston and the outer end of the cylinder to cushion said piston, and a second electrode arranged within the path

of movement of the first, and movable laterally with respect thereto, the engaging faces of the electrodes being rounded or cam-shaped to permit the wiping of one past the other.

3. In a sparker for explosive-engines, a cylinder having its open inner end in communication with the explosion-chamber of the engine, a piston within the cylinder, an electrode carried by said piston, a compression-spring tending to force the electrode in the direction of the explosion-chamber, means for adjusting the stress of said spring, and a second electrode disposed in the path of movement of the first, and movable laterally with respect thereto, the engaging faces of the electrodes being rounded or cam-shaped to permit the wiping of one past the other.

4. In a sparker for explosive-engines, a cylinder having its open inner end in communication with the explosion-chamber of an engine, a piston disposed within the cylinder, an electrode carried by the piston, the outer end of said electrode being threaded, a nut carried by the threaded portion of the electrode to adjust the extent of the stroke of the piston, and a second electrode arranged in the path of movement of the first.

5. In a sparker for explosive-engines, a cylinder having its open inner end in communication with the explosion-chamber of an engine, a piston arranged in the cylinder, an electrode carried by said piston, a cap-piece, and a nut forming a closure for the outer end of said cylinder, the cap-piece being provided with an electrode-guiding opening and the nut having recesses, a yoke member having its lower end seated in the nut-recesses and provided with an electrode-guiding opening, the outer portion of the electrode being threaded and extending loosely through said opening, a compression-spring surrounding the electrode, a nut for adjusting the tension of the spring, a second nut mounted on the threaded portion of the electrode and serving as a means for adjusting its stroke, and a second electrode disposed in the path of movement of the first electrode.

6. In a sparker for explosive-engines, a cylindrical casing, a plug adapted to a threaded opening in the casing, a sleeve disposed within the plug and insulated therefrom, a bar-electrode having limited longitudinal play within the sleeve, a spring tending to move said electrode in one direction, means for limiting longitudinal movement of the electrode, a piston disposed within the casing, and a second electrode carried by said piston.

7. In a sparker for explosive-engines, a cylindrical casing, a plug adapted to a threaded opening in the casing, a sleeve disposed within and insulated from the plug, a bar-electrode having limited longitudinal play in the sleeve, a guiding-yoke at the outer end of the bar, and a compression-spring tending to force the electrode into the casing, a piston dis-

posed within the casing, and a second electrode carried by said piston.

8. In a sparker for explosive-engines, a cylindrical casing, a relatively stationary electrode carried thereby, a piston disposed within the casing, a cap-plate and nut forming a closure for one end of the casing, a yoke supported by the nut, an electrode carried by the piston and having a threaded outer end guided by the yoke, a spring tending to move the second electrode in the direction of the first, and a nut carried by the threaded end of the electrode for adjusting the stroke of the piston.

9. In a sparker for explosive-engines, a cylindrical casing, a plug adapted to a threaded opening therein, a sleeve carried by and insulated from the plug, a bar-electrode mount-

ed in the sleeve, a spring tending to force the electrode into the casing, a piston disposed within said casing, an electrode carried by the piston, a spring carried by the electrode at a point above the piston and forming a cushion therefor, and a movable plug disposed in a threaded opening in the casing at a point opposite the bar-electrode, substantially as specified.

In testimony that I claim the foregoing as my own I have hereto affixed my signature in the presence of two witnesses.

GEORGE A. WEST.
